UNITED STATES PATENT OFFICE.

JOSEPH SPROUL, OF JERSEY CITY HEIGHTS, NEW JERSEY, ASSIGNOR TO KAST INSETTING AND GATHERING MACHINE CO., OF NEW YORK, N. Y., A CORPORATION OF DELAWARE.

CONVEYER CHAIN.

Application filed December 28, 1922. Serial No. 609,474.

To all whom it may concern:

Be it known that I, JOSEPH SPROUL, a citizen of the United States of America, and a resident of Jersey City Heights, New Jersey, have invented new and useful Improvements in Conveyer Chains, which invention is fully set forth in the following specification.

The present invention is an improvement 10 in the mechanism for conveying groups of signatures to a stitching device or other instrumentality, and particularly is an improvement in the pusher member that engages the rear edges of the signatures of the 15 successive groups.

These pusher members are carried by the endless conveyer that progresses the groups of signatures from the point where they are deposited on the conveyer to the support on 20 which they are stitched or otherwise operated upon. At the point where the groups of signatures pass onto the support on which they are stitched, the endless conveyer passes around a sprocket wheel and its 25 direction of travel passes from the horizontal to the vertical. This is the point at which jamming usually takes place; that is to say, it frequently happens that for one reason or another a group of signatures 30 will be stopped at this point while the conveyer carrying the pusher members will continue to move. In the construction heretofore employed, the pusher pins have frequently been broken off under these conditions, the links of the conveyer have been 35 wrenched out of alinement, and even the sprocket wheel over which the conveyer chain passes at this point has been injured. Jams of this kind accordingly have been 40 productive not only in loss of time while the difficulty is being attended to, but also in injury to the device.

The object of the present invention is to provide a pusher member which will firmly 45 engage the rear edges of the signatures of a group and operate in the normal functioning of the parts with all of the effectiveness of a rigid pusher member and yet which will, in the event of a jam, yield and 50 pass under the jammed signature group, thus protecting the device from injury and minimizing the seriousness of such an occasion and the time which is necessary to 55 remove the jammed signature group and permit the machine to function normally.

The invention will be better understood by reference to the accompanying drawings illustrating one expression of the inventive idea, and wherein—

Fig. 1 is a side elevation showing a conveyer equipped with improved pusher members and also the parts of the apparatus where jams usually occur;

Fig. 2 is a perspective view of a conveyer equipped with the improved pusher member; and

Fig. 3 is a cross-section.

Referring to the drawings, wherein like reference numerals indicate like parts, 5 indicates a support such as is customarily 70 used on "stitcher feeders" and on which the groups of signatures are placed and from which they are removed to an endless conveyer 6 by a pusher member 7. This endless conveyer is usually constituted by 75 a plurality of links which are connected together in any suitable manner and which pass around a sprocket wheel 8 mounted at 9 in a standard 10. The conveyer 6 is mounted on any suitable support 11 and the 80 signatures are progressed by said conveyer from the dotted line position A on the support 5 to the dotted line position B on the main saddle or support 12. In Fig. 1 the conveyer is shown passing around the 85 sprocket wheel 8 and at the point where it changes from its horizontal to its vertical traverse. It is at this point that the jams occur for the most part and where the damage 90 occurs by reason of the unyielding pusher, as heretofore employed, continuing to move and press against the group of signatures that has been stopped for one reason or another.

The pusher member constituting the present invention is normally unyielding and yet, in the event of a jam, it yields in the line of travel of said conveyer and passes under the jammed group, thus protecting the parts from injury and minimizing the damage to 100 the group of signatures and the time necessary to clear away the obstacle. As illustrated, this pusher consists of a closely wound spiral wire that may, if desired, be provided at its outer end with a plug 13 of 105 metal or other material for the purpose of stiffening the pusher. The pusher is fastened in any suitable manner in one face of the conveyer 6, and preferably a pusher of this kind is arranged in each face of the con- 110

veyer in the same cross-sectional plane. Preferably, these pushers pass into openings or orifices 14 in the faces of the conveyer 6 and are secured in place in these openings by the engagement of the spiral convolutions operating as threads. In other words, the pusher is simply screwed into the opening. If the metal of the conveyer is thin, it is only necessary to drill a hole 10 through the same for the reception of the pushers, through it has been found desirable to also tap a thread or two in the walls of said conveyer to cooperate with the convolutions of the pusher. These pushers are 15 readily manufactured on a lathe by spirally winding a strip of wire around a rod or former and then cutting off desired lengths of the tightly wound wire.

There is thus provided a simple and highly 20 efficient pusher member which is readily screwed in or out of its seat and which functions perfectly under all normal conditions and yields in the event of a jam to protect the device. The simplicity of the pusher 25 renders it possible to manufacture the same very cheaply and quickly, and also to place them in position or remove them from their seats expeditiously and simply.

While, for the purpose of illustration, 30 one expression of the inventive idea has been

illustrated and described, it is to be understood that the invention is not limited thereto, and that the inventive idea may be embodied in various mechanical expressions 35 within the limits of the appended claims.

What is claimed is:—

1. In a device of the character described, a movable conveyer for progressing groups of signatures, a pusher member mounted on 40 said conveyer and engaging the rear edges of the signatures, said member being composed of a spirally wound wire.

2. In a device of the character described, a movable conveyer for progressing groups 45 of signatures, a pusher member mounted on said conveyer and engaging the rear edges of the signatures, said member being composed of a spirally wound wire and a stiffening plug in the outer end thereof. 50

3. In a device of the character described, a movable conveyer for progressing groups of signatures and provided with apertures, a pusher member mounted on said conveyer and engaging the rear edges of the signatures, said member being composed of a spirally wound wire and being screwed into 55 said apertures.

In testimony whereof I have signed this specification.

JOSEPH SPROUL.
